G. A. MONTGOMERY

LIFTING DEVICE FOR TEMPER SCREWS

Filed April 29, 1924

Inventor:
Gustavus A. Montgomery
by George Steyer
Attorneys.

UNITED STATES PATENT OFFICE.

GUSTAVUS A. MONTGOMERY, OF TITUSVILLE, PENNSYLVANIA.

LIFTING DEVICE FOR TEMPER SCREWS.

Application filed April 29, 1924. Serial No. 709,931.

To all whom it may concern:

Be it known that I, GUSTAVUS A. MONTGOMERY, a citizen of Finland, residing at Titusville, in the county of Crawford and 5 State of Pennsylvania, have invented new and useful Improvements in Lifting Devices for Temper Screws, of which the following is a specification.

This invention relates generally to the 10 temper screws employed in connection with well drilling apparatus, but more particularly to the lifting mechanism employed therewith.

One of its objects is to provide an improved lifting or counterbalancing mechanism for temper screws which is efficient, reliable and automatic in operation.

Other objects of the invention are to provide a device of this character which is 15 simple, strong and durable in construction, and which is readily applicable to the temper screws now in use without materially altering their construction.

In the accompanying drawings:

Figure 1 is a longitudinal sectional view 20 of the device, taken in the plane of line 1-1, Fig. 2. Figure 2 is a horizontal section on line 2-2, Fig. 1. Figures 3 and 4 are transverse vertical sections taken on the 25 correspondingly numbered lines in Fig. 1.

Similar characters of reference indicate corresponding parts throughout the several views.

Referring now to the drawings, the 30 numeral 10 indicates the temper screw which may be of any well-known construction, being provided at its upper end with the customary cross bar 11 seated in the saddle-plates 12 secured to the front end of the walking beam 13 of the drilling apparatus. The stem 14 of the temper screw has a vertical bore 15 through which the suspension cable 16 passes, the latter being fastened at its lower end to an eye 17 or other appropriate coupling attached to the upper end of the temper screw.

The improved lifting mechanism is preferably mounted on the walking beam near the front end thereof and consists of a longitudinally divided casing or housing of two sections 18, 19, jointed by bolts 20 and se-

curely fastened to said walking beam by bolts 21 or other suitable fastenings. This casing is closed on all sides with the exception of the lower portion of its front side, 55 which is left open, as shown at 22, for the passage of the cable 16. Journaled transversely in bearings in the front portion of said casing is a horizontal shaft 23 carrying a winding drum or sheave 24 to which 60 the upper end of the suspension cable is fastened and about which it is adapted to be wound and unwound during the act of raising and lowering the temper screw. A pinion 25 is also mounted on the drum-shaft 65 and meshes with a gear 26 secured to a rewind shaft 27 parallel to said drum-shaft and journaled in the rear portion of the casing.

Means are provided for automatically imparting motion to the rewind shaft 27 and 70 rotating the sheave 24 in the proper direction to elevate the temper screw whenever the customary screw-operating mechanism (not shown) is disengaged therefrom. For 75 this purpose, the rewind shaft has a pinion 28 thereon which engages a horizontally disposed gear-rack 29 movable lengthwise of the casing and the walking beam. This gear-rack is guided in an opening 30 formed 80 in an extension 31 of the casing-section 18 and is adapted to project into a cylindrical portion 32 disposed in rear of and longitudinally in line with said extension. At 85 its rear end the gear-rack is provided with a rod 33 having a washer 34 and a nut 35 at its free end, and interposed between said washer and an inturned flange 36 located at the intersection of the extension 31 with its cylindrical portion 32 is a coiled spring 37 which tends constantly to move said gear-rack rearwardly for rotating the sheave 24 in a counter-clockwise direction to elevate the temper screw. A screw-plug 38 is applied to the open rear end of said cylindrical portion against which the washer 34 is adapted to abut for limiting the rearward movement of the rack.

Briefly stated, the operation of the device is as follows, assuming the parts to be 90 in their normal position, as shown by full lines in the drawings, wherein the temper 95

screw 10 is in its elevated position and the gear-rack 29 in its extreme rearward position. When lowering the temper screw by means of the usual screw-operating mechanism, the sheave 24 is rotated in a clockwise direction and through the medium of the reduction gearing 25, 26 and 28 the rack is moved forwardly in the direction of the arrow, Fig. 1, compressing the spring 37. 10 When the screw reaches its extreme lower position and its operating mechanism is released, the spring causes the automatic return of the screw to its initial position.

This improved screw-elevating device is 15 simple and compact in construction, it can be readily employed in connection with existing temper screws by simply drilling the cable-passages 15 in the stems thereof, and its parts are so organized and arranged that 20 they are not liable to get out of order. Furthermore, all parts of the device are enclosed and out of the way where they do not interfere with those working around the drilling apparatus.

25 I claim as my invention:

1. The combination with the walking beam of a drilling apparatus and the temper screw supported thereby, of an elevating device for the temper screw, comprising a 30 casing mounted on the walking beam, a winding drum carried by said casing, a flexible member connected at one end to said temper screw and at its other end to said drum, and means in said casing operatively 35 connected to said drum and tending constantly to rotate the latter in a direction to elevate the temper screw.

2. The combination with the walking beam of a drilling apparatus and the temper 40 screw supported thereby, of an elevating device for the temper screw, comprising a casing mounted on the walking beam, a winding drum carried by said casing, a flexible member connected at one end to 45 said temper screw and at its other end to said drum, and a yieldable member in said casing operatively connected to said drum for resisting rotation of the latter in a direction to lower the temper screw.

50 3. The combination with the walking beam of a drilling apparatus and the temper screw supported thereby, of an elevating device for the temper screw, comprising a 55 casing mounted on the walking beam, a winding drum carried by said casing, a flexible member connected at one end to said temper screw and at its other end to said drum, a yieldable member guided in said casing for movement lengthwise thereof, 60 and driving mechanism interposed between said drum and said yieldable member, the latter resisting rotation of the drum in a direction to lower the temper screw.

65 4. The combination with the walking beam of a drilling apparatus and the temper

screw supported thereby, of an elevating device for the temper screw, comprising a 70 casing mounted on the walking beam, a winding drum carried by said casing, a flexible member connected at one end to said 75 temper screw and at its other end to said drum, a gear rack guided in said casing for movement lengthwise thereof, gearing interposed between said drum and said gear rack, and means tending to urge said rack in a direction to elevate the temper screw.

5. The combination with the walking beam of a drilling apparatus and the temper screw supported thereby, of an elevating device for the temper screw, comprising a 80 casing mounted on the walking beam, a winding drum carried by said casing, a flexible member connected at one end to said 85 temper screw and at its other end to said drum, a gear rack guided in said casing for movement lengthwise thereof, reduction gearing interposed between said drum and said gear rack, and a coil spring applied to said rack for moving the same in a direction 90 to elevate the temper screw.

6. The combination with the walking beam of a drilling apparatus and the temper screw supported thereby, of an elevating device for the temper screw, comprising a 95 casing mounted on the walking beam and having an extension at one side thereof, a winding drum mounted in said casing and having a cable wound thereon connected at its free end to the temper screw, a gear 100 rack guided in said casing-extension for movement lengthwise thereof, reduction gearing in the casing and interposed between said drum and said gear rack, and a coil spring applied to said rack for moving the same in a direction 105 to elevate the temper screw.

7. An automatic lifting device for temper screws, comprising a casing, a winding drum journaled in said casing and adapted for connection with the temper screw, a spring-pressed gear rack operatively connected with 110 said drum and tending constantly to rotate it in a direction to lift the temper screw, and gearing between said drum and said rack.

8. An automatic lifting device for temper screws, comprising a casing, parallel shafts journaled in said casing, a winding drum mounted on one of said shafts and including a cable adapted for connection with the temper screw, a pinion on said drum-shaft, a gear and pinion mounted on the other shaft, said gear meshing with said drum-shaft pinion, a gear rack guided on said casing and meshing with the pinion of said second-named shaft, and means engaging said rack and tending constantly to move it in a direction to lift the temper screw.

9. An automatic lifting device for temper screws, comprising a casing constructed of 120

jointed sections, one of the sections carrying an extension, parallel shafts journaled in said casing, a winding drum mounted on one of said shafts and including a cable adapted for connection with the temper screw, a pinion on said drum-shaft, a gear and pinion mounted on the other shaft, said gear meshing with said drum-shaft pinion, a gear rack guided in said section-extension and meshing with the pinion of said second-named shaft, and a coil spring contained in said extension and applied to said gear rack for constantly urging the latter in a direction to lift the temper screw. 10

GUSTAVUS A. MONTGOMERY.
